UNITED STATES PATENT OFFICE.

CHARLES HENRY BROWN, OF RANGER, TEXAS.

GRAPPLE.

1,421,159.

Specification of Letters Patent. Patented June 27, 1922.

Application filed December 18, 1920. Serial No. 431,722.

To all whom it may concern:

Be it known that I, CHARLES H. BROWN, a citizen of the United States, and a resident of Ranger, in the county of Eastland and State of Texas, have invented certain new and useful Improvements in Grapples.

This invention relates to grapples especially adapted for use in recovering small articles such as undreamer lugs and small 10 chippings of cases.

The invention froming the subject matter of this application aims to provide a tool of the class described having simple means for gripping an under-reamer lug or the like to permit of the removal of the under-reamer lug should the same become detached while drilling a hole.

A further object of the invention is to provide a device of the class described having 20 simple means whereby the same may be adjusted for use in connection with holes of various sizes.

A further object of the invention is to provide a device of the class described which is 25 simple in use, of highly simplified construction and cheap to manufacture.

Other objects and advantages of the invention will be apparent during the course of the following description.

30 In the accompanying drawing forming a part of this application and in which like numerals are employed to designate like parts throughout the same,

Figure 1 is a longitudinal sectional view 35 through the device in use.

Figure 2 is a detail sectional view through the same, the view illustrating the device being engaged with an under-reamer lug.

Figure 3 is an end elevation of the device.

40 Figure 4 is a horizontal sectional view taken on the line 4—4 of Figure 1.

Figure 5 is a detail sectional view through the device, illustrating the means whereby the device may be adjusted for use in connection with holes of various diameters.

45 In the drawing wherein for the purpose of illustration is shown the preferred embodiment of the invention, the numeral 10 designates the shank of the device, which shank is adapted for connection with a controlling member 12 through the medium of an attaching member 13. A barrel 14 is formed on the forward end of the shank 10 and is adapted to be introduced into a hole 50 being drilled when it is desired to recover an

under-reamer lug or other small article. The member 14 which is of tubular formation has its forward end open and has its rear end closed and formed with a boss 15 to which a plurality of spaced parallel arms 16 are 60 welded or otherwise secured. The spaced parallel spring arms 16 extend forwardly from the boss 15 and terminate beyond the forward end of the tubular member 14 so as to be in a position to grip an under-reamer 65 lug 17. The extended portions of the spring arms 16 are formed with outwardly directed triangular barbs 18 one of which is adapted to be received within the opening 19 in the rear portion of the under-reamer lug 17. As 70 the tubular member 14 is introduced into the opening 20, the forward beveled portions of the triangular bar 18 contact with the rear portion of the lug 17 whereupon one of the spring arms moves inwardly and the barb of 75 that arm is consequently received within the opening 19, whereby the barb is securely connected to the lug.

As illustrated in Figure 2, the collar 22 is 80 threaded on the forward portion of the tubular member 14 and is adjustable with relation to the same so that the distance between the barbs 18 and the collar 22 may be varied to meet operating conditions. Since the collar 22 forms a part of the tubular 85 body 14 it might be stated that the tubular body 14 is adjustable with relation to the barbs. When it is desired to use the device in holes somewhat wider than the diameter of the tubular member an annular shoulder 90 24 may be secured to the forward portion of the tubular member and the collar 22 through the medium of bolts 26 which are adjustable within longitudinal slots 27 formed in the forward portion of the tubular body 14. 95 The annular shoulder 24 when applied increases the diameter of the tubular body of the forward portion of the same and thereby serves to guide the tubular body when moved forwardly or rearwardly.

100 The spring arms may be spread to correspondingly spread the barbs 18 when using the device in wide holes. The means for spacing the barbs 18 includes an adjusting member 27 which is located between the ends 105 of the spring arm to contact with the offset portions 28 of the same. The adjusting member 27 which is in the form of a cone is mounted on a screw threaded rod 30. Adjusting member 27 is held in a set position 110

by a nut 31 against the tension of a retractile coiled spring 32 mounted on the member 30 inwardly of the spring arms.

When it is desired to increase the zone of action of the barbs it is merely necessary to advance the nut on the rod 31 for moving the adjusting member 27 rearwardly. By thus moving the adjusting member 27 rearwardly the same is brought into contact with the offset portions 28 so as to move the spring arms outwardly. With the device thus adjusted the same may be used in connection with holes of a diameter considerably greater than the diameter of the tubular casing 14.

In the use of the device, the same is inserted into a hole being drilled for the purpose of recovering the lug 17 which in some cases lodges as illustrated in Figure 2.

20 When one of the barbs 18 engages with the lug, the device is moved rearwardly and the lug assumes the position illustrated in Figure 1. Pieces of casing and the like may also be readily removed by means of 25 this device.

Having thus fully described my invention what I claim as new is:—

1. A device of the class described comprising a tubular member having its forward end open, and a plurality of spring arms carried by the tubular member and formed with barbs, the forward portion of said tubular member being provided with a collar adjustable with relation to said 35 barbs.

2. A device of the class described comprising a body having its forward end open, a plurality of spring arms carried by said body and terminating beyond the forward 40 end of the same, the forward end portions of said spring arms being formed with barbs, the forward portion of said tubular member being provided with a collar adjustable with relation to said barbs.

45 3. A device of the class described comprising a body having its forward end open, a plurality of spring arms arranged in said body and terminating beyond the forward end of the same, the extended forward 50 end portions of said spring arms being formed with gripping means, and an adjusting device associated with said arms, the forward portion of said tubular member being provided with a collar adjustable with relation to said barbs.

55 4. A device of the class described comprising a body, a plurality of spring arms carried by said body and formed with gripping means beyond the forward end of said body, and means whereby the space between the barbs and the body may be varied.

60 5. A device of the class described comprising a tubular member having a boss, a plurality of spring arms secured to said boss 65 and terminating beyond the forward end of

said tubular member, the forward end portions of said spring arms being provided with barbs, a collar threaded on said tubular member and adjustable with relation to said barbs, and adjusting means for said barbs. 70

6. A device of the class described comprising a tubular member having a centrally arranged boss at its rear end, a plurality of spaced spring arms secured to said boss and terminating beyond the forward end 75 of said tubular member, the forward ends of said spring arms being formed with outwardly directed barbs, the intermediate portions of said spring arms being offset, and an adjusting device arranged between said arms and engaged with the offset portions 80 of the same.

7. A device of the class described comprising a tubular member having its forward end open, a bore arranged centrally in the 85 rear portion of said tubular member, a plurality of spring arms secured to said boss and terminating beyond the forward end of said tubular member, the forward portions of said tubular member being provided 90 with gripping means, the intermediate portions of said spring arms being offset, an adjusting device in the form of a cone arranged between said spaced arms to contact with the offset portion of the same, an adjusting nut contacting with said adjusting device, a rod extending through said adjusting device and having threaded engagement with said nut, and a spring arranged on said rod and contacting with said adjusting device. 95

8. A device of the class described comprising a tubular member, a plurality of spring arms extending through the tubular member and having its intermediate portions offset, 105 an adjusting device engaged with the intermediate offset portions of said spring arms, and spring means to urge the adjusting device to its inoperative position.

9. A device of the class described comprising a tubular member, a plurality of spring arms extending through the tubular member and having its intermediate portions offset, an adjusting device engaged with the intermediate offset portions of said spring arms, 110 spring means to urge the adjusting device to its inoperative position, and means whereby the effective length of the tubular member may be varied.

10. A device of the class described comprising a tubular member having a boss, a plurality of spring arms connected to said boss and terminating beyond the tubular member, a rod connected to said boss between said arms, an adjusting cone arranged 115 on said rod and engaged with the offset portions of said spring arms, and an adjusting nut threaded on said rod for adjusting said adjusting member. 125
